UNITED STATES PATENT OFFICE

155,174

DESIGN FOR AN ELECTRIC OUTLET PLUG

Lewis Earl Martin, Lewes, Del.

Application April 27, 1948, Serial No. 145,997

Term of patent 3½ years

(Cl. D26—1)

To all whom it may concern:

Be it known that I, Lewis Earl Martin, a citizen of the United States, residing at Lewes, in the county of Sussex and State of Delaware, have invented a new, original, and ornamental Design for an Electric Outlet Plug, of which the following is a specification, reference being had to the accompanying drawing, forming part thereof.

Figure 1 is a perspective view of an electric outlet plug, showing my new design.

Figure 2 is a side elevational view thereof, and Figure 3 is a top plan view of the same.

I claim:

The ornamental design for an electric outlet plug, as shown.

LEWIS EARL MARTIN.
